Primary Examiner — Sandra Snapp

Assistant Examiner — Bryan N. Melvin

(57) **CLAIM**

The ornamental design for a charging stand, as shown and described.

DESCRIPTION

1.1 is a front view of a charging stand, showing our new design;

1.2 is a rear view thereof;

1.3 is a left side view thereof;

1.4 is a right side view thereof;

1.5 is a top view thereof;

1.6 is a bottom view thereof;

1.7 is a perspective view thereof; and

1.8 is a perspective view, shown in an open state.

The broken lines depict portions of the charging stand that form no part of the claimed design.

1 Claim, 8 Drawing Sheets
